UNITED STATES PATENT OFFICE.

JAMES B. CONDLEY AND JAMES G. SMITH, OF FRESNO, CALIFORNIA.

FINGER ATTACHMENT.

1,261,706.

Specification of Letters Patent. Patented Apr. 2, 1918.

Application filed May 25, 1917. Serial No. 171,021.

To all whom it may concern:

Be it known that we, JAMES B. CONDLEY and JAMES G. SMITH, citizens of the United States, residing at Fresno, in the county of Fresno and State of California, have invented new and useful Improvements in Finger Attachments, of which the following is a specification.

This invention relates to finger pads and has for its object the provision of a pad adapted to be fitted upon the finger for use in counting money, sheets of paper, turning the leaves of a book, or for any other purpose where it is necessary to separate sheets one at a time.

Another object of the invention is the provision of a finger pad which is provided with transversely arranged ribs or teeth upon its under side or working surface, so formed and arranged as to insure separation of a single sheet or page from a stack or book, when moved in contact therewith, the novel construction of these ribs providing a right angular wall upon one side and an inclined wall upon the opposite side.

A further object is to provide means carried by the pad for grasping the same to facilitate positioning of the pad upon the finger.

With the above and other objects in view the invention consists of a finger pad of thimble like formation, which is adapted to fit snugly upon the end of the finger, the said pad being formed of elastic material and provided with transversely arranged teeth or ribs upon its under side or working surface, the walls of the ribs facing the open end of the thimble being substantially right angular, while the opposite walls are inclined at an angle thereto, so as to insure a positive grasp upon the surface of the paper or other article to be separated.

The invention is further provided with a projection extending through the edge of the open end of the thimble by means of which it may be grasped for positioning the pad for use.

In the drawings,

Figure 1 is a perspective view of the invention applied; 50

Fig. 2 is a similar view of the invention removed; and

Fig. 3 is an enlarged longitudinal central sectional view of the improved pad or thimble. 55

Referring to the drawings in detail, the invention consists of a pad preferably composed of elastic material of thimble like formation, the body of this pad being indicated by the numeral 10. As shown it is circular in cross-section and is provided with an open end 11 and a closed semi-spherical end 12, this latter end being provided with an aperture 13 for the admission of air, for the purpose of preventing undue heating of the end of the finger of the wearer, or the creation of a vacuum within the pad when in use. 60

The under side or working surface of the pad is formed with transversely arranged ribs or teeth 14, the rear walls or wall facing the open end of the thimble being substantially right angular with respect to the body portion 10. This right angular wall is designated by the numeral 15 and the opposite wall by the numeral 16. This last mentioned wall is disposed at an angle with respect to the wall 15 and provides a sharpened edge 17 for the ribs or teeth. By the arrangement of these teeth, their contact with the surface of the sheet of paper, will cause the same to be drawn singly from the stack or pile, so that the operation of counting or turning is greatly facilitated. 70

The open end of the pad is formed with a projecting lip or tongue 18 to aid in positioning the pad upon the finger. 75

It is believed that from the foregoing description taken in connection with the accompanying drawings the construction, uses and advantages of the invention will be apparent and that a more extended description is unnecessary. 80

Having described the invention, what is claimed is:

1. An improved article of manufacture 95

comprising an elastic thimble adapted to cover the entire end of the finger and transversely arranged ribs provided with right angular walls upon one surface and inclined walls upon the opposite surface.

2. An improved article of manufacture comprising an elastic thimble adapted to cover the entire end of the finger, transversely disposed ribs formed upon and pro-

jecting beyond the outer surface of the thimble, the said ribs having a right angular face and an inclined face, the right angular face being disposed toward the open end of the thimble.

In testimony whereof we affix our signatures.

JAMES B. CONDLEY.
JAMES G. SMITH.
